Hiram Holt, of Weld in the County of Oxford, Maine

Letters Patent

The schedule referred to in these Letters Patent and making part of the same, containing a description in the words of the said Hiram Holt, himself of his improvement in a machine for getting out clover seed and other grass seed and small grain

to all whom these presents shall come.

Be it known that I, Hiram Holt of Weld in the County of Oxford and State of Maine, have invented a new and useful improvement in a Machine for getting out clover, Hood, and other grass seed, and small grain, and the following is a full and exact description thereof. Said Machine consists of a cylinder two feet long by two feet in diameter the size and proportion being varied and made larger or smaller according to the power to be applied. Said cylinder rests horizontally and on quadrants in the centre of each end. The circumference or concavity of said cylinder is covered with sheet iron placed in the manner of a grater excepting a portion of the same on the upper side which is so constructed as to present a rugged ^{in operation} getting or clafford like projecting surface placed in such manner as to gather in the material for grinding. - The action of said cylinder will scribe part of a circle backwards and forwards. On the outside and facing the concavity of said cylinder (excepting a space left open at the top) over the above named rugged surface for feeding and another space left open underneath as an outlet for the seed both being of the length of the cylinder. is an investment of shell, adapted to the concavity said cylinder, and covers, on the inner or concave side with sheet iron placed after the manner of a grater and having a gauge attached in order to move the said investment nearer to, or further from said cylinder as occasion may require. And the said Holt says, what I claim is new and as my discovery and invention

is the whole cylinder its moving back and forward making a part of a revolution, each way, acting and being acted upon by the movement, on each side thereby making a double grinding surface, that is a grinding surface on each side of the cylinder, I do not claim the motion back and forth in particular, otherwise that will cause the cylinder to operate alternately on each side. I do claim an investment facing the cylinder on each side and I claim the whole cylinder as applied to the said investments.

Attest witness my hand at W.L.D., County of Oxford & State of Maine this 23rd of April A.D. 1835.
